UNITED STATES PATENT OFFICE

WILLIAM F. POTTER, OF ST. CLOUD, MINNESOTA

SIGNAL

Application filed February 7, 1931. Serial No. 514,250.

This invention relates to mechanical signals, designed for use in connection with motor vehicles, the primary object of the invention being to provide means for indicating the direction of travel to be taken by the vehicle equipped with the signal.

An important object of the invention is to provide a signal of this character which may be readily and easily operated, in such a way as to permit the free use of both hands of the operator, to manipulate driving apparatus in making a turn.

Another object of the invention is to provide a signal of this character including cylinders and pistons, novel means being provided for creating a vacuum in the cylinders, to move the movable indicating member, into and out of operation.

A still further object of the invention is the provision of a signal or indicator where in the movable indicating arm, will be completely housed and protected against the elements, when in its inactive position.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings: Figure 1 is an elevational view illustrating a signal or indicator constructed in accordance with the invention, as positioned on a motor vehicle.

Figure 2 is a sectional view through the valve mechanism.

Figure 3 is a rear elevational view of the valve housing.

Figure 4 is a vertical sectional view through the valve housing.

Figure 5 is a longitudinal sectional view

through the outer casing of the housing in which the indicating arm is mounted.

Figure 6 is a longitudinal sectional view through the housing and indicating arm.

Figure 7 is a sectional view taken on line 7-7 of Figure 6.

Figure 8 is a sectional view taken on line 8-8 of Figure 6.

Referring to the drawings in detail, the signal comprises a pair of elongated housings indicated by the reference character 5, the housings being preferably rectangular in cross section. These housings are arranged at opposite sides of the body of the vehicle, and disposed preferably within the visor of the vehicle, and since these housings are identical, only one of the housings will be described in detail.

Slidably mounted within the body portion 5, is a hollow indicating arm 6 which is provided with rollers 7 that engage the inner surfaces of the housing 5. At the forward end of the housing 5, are rollers 8 on which the forward end of the indicating arm 6 rests.

Disposed within the housing is a cylinder 9, the forward end of the cylinder extending into the lamp housing 10, in which the lamp 11 is mounted. Rollers 12 are mounted within the lamp housing 10, and engage the inner surface of the hollow indicating arm to further reduce friction between the indicating arm and its support, to insure an indicator which will be exceptionally sensitive to the action of the operating medium.

The outer end of the hollow indicating arm 6, is closed by means of the end wall 13, to which wall the rod 14 is connected, the rod 14 carrying the piston 15 at its inner end. Thus it will be seen that due to this construction, the hollow indicating arm 6 will be moved to its active or extended position when the piston 15 moves to the outer end of the cylinder 9.

Cut out portions are formed in the sides of

the hollow indicating arm 6, and are so constructed that they define indicating arrows 16, at opposite sides of the arm 6. The reference character 17 designates a tube that connects with the cylinder 9 near the outer end thereof, the opposite end of the tube 17 being connected with the body portion or housing 18 of the valve, to be hereinafter more fully described. The reference character 19 designates a tube that communicates with the cylinder 9, at the inner end of the cylinder, the opposite end of the tube being in communication with the housing 18, at 20. The reference character 21 designates a tube that connects with the valve housing 18, at one end thereof, the opposite end of the tube 21 extending to the vacuum tank 22 of the vehicle, so that the vacuum created in the vacuum tank 22, will act on the piston 15, to move the piston longitudinally of its cylinder, according to the end of the cylinder in which the vacuum is produced.

The rotary valve is indicated generally by the reference character 23, the valve being hollow and supplied with an operating handle 24, whereby the valve may be rotated, to operate the valve.

Tubes 25 and 26 merge from a common opening 27 formed in the periphery of the valve 23, from where the tubes 25 and 26 curve laterally in opposite directions, where they communicate with openings 28 which are also formed in the periphery of the valve housing.

Openings 29 are also formed in the periphery of the valve 23 and are of lengths to bridge the inner ends of the pipes 17 and the intake ports 30 of the valve housing, so that air may be drawn into one end of the cylinder, as air is being drawn from the cylinder at the opposite end. In order that the valve 23 may be restricted in its movements, a set screw 31 is provided, which extends through the housing to the valve, and is adapted to engage the shoulders 32 at the ends of the cut out portion 33.

As clearly shown by Figure 4 of the drawings, the handle 24 extends inwardly, defining a shank 34, which shank extends through the disk 35 constructed of insulating material, the disk carrying contact points 36 and 37, which are in circuit with the lamp 11, through the wires 38 and 39 respectively, the latter wire constituting the ground wire. Carried by the shank 34, are the contact arms 38', which arms are adapted to bridge certain of the contacts points 36 and 37, to automatically light the lamp 11 within the indicating arm. It will of course be understood that these contacts points 36 and 37 are so arranged that when the handle 24 is operated to move the valve to move the indicating arm at the right of the vehicle, to its active position, the lamp in the lamp housing 10 at the right side of the vehicle, will be lighted. When the

valve is moved to operate the indicating arm at the left side of the vehicle, the lamp in this indicating arm, will be automatically lighted.

It will of course be understood that the valve housing is so positioned that the operator of the vehicle will have easy access to the handle 24.

The operation of the signal is as follows:

Assuming that the indicating arms are in their inactive positions within their housings, and the vehicle is to make a left hand turn, the operator moves the valve member to bring the opening 29 to a position to bridge the inner ends of the tubes 17 and 21, which movement will bring the opening 28 to a position to bridge the inner end of the tube 20 and intake port 30. It follows that the vacuum created in the tube 21 will act to draw the air from the outer end of the cylinder at the left side of the vehicle, moving the indicating arm to a position as shown by Figure 1 of the drawings. As the piston 15 moves to its outermost position, air will be drawn into the valve housing, through the port 30 and tube 19, from where the air will enter the cylinder, displacing the vacuum within the cylinder at the inner side of the piston. It will of course be understood that simultaneously with the moving of the indicating arm to its active position, the lamp 11 will be illuminated, illuminating the indicating arm, so that the signal will be clearly visible at night. When it is desired to return the arm to its normal or inactive position, the handle 24 is operated to move the valve member to a position as shown by Figure 2 of the drawings, whereupon the tube 19 will be brought into registry with the tube 21, creating a vacuum within the inner end of the cylinder, and causing the piston 15, to be moved towards the inner end of the cylinder.

The indicating arm is now moved inwardly and completely housed within the housing. It will be obvious that air will be drawn into the opposite end of the cylinder through the port 30 and pipe 17.

While I have described the operation of the valve and signal for indicating the direction of travel of the vehicle to the left, it is to be understood that by moving the handle 24 in the opposite direction, the tubing and ports will be brought into registry to operate the signal or indicating arm at the opposite side of the vehicle.

I claim:

A signal comprising a cylindrical casing having an open outer end, a cylinder secured within the cylindrical casing and extended to a point near the open end of the cylindrical casing, a lamp housing mounted at one end of the cylinder and supported in spaced relation with the cylindrical casing, a tubular arm having an open inner end fitted over the lamp housing, the outer end of the tubular arm being closed, a rod connected with the

closed end of the tubular arm and disposed within the cylinder, a piston on the inner end of the rod to move the rod through the cylinder, means for controlling a vacuum within the cylinder to move the rod and tubular arm, and a lamp in the lamp housing for illuminating the tubular arm.

In testimony that I claim the foregoing as my own, I have hereto affixed my signature.

WILLIAM F. POTTER.
